WAISTBAND CONSTRUCTION FOR
GARMENTS

Ernest A. De Rose, Mount Vernon, N. Y.

Application June 9, 1941, Serial No. 397,173

4 Claims. (Cl. 2—237)

This invention relates to wearing apparel and relates more particularly to garments, such as trousers, slacks, shorts, skirts, bathing trunks and the like.

Most ready-to-wear and custom garments of the above types are provided with pleats or pleated portions which must be taken into account during the designing, cutting and other steps of manufacture of the garment. In order to provide for such pleats it is necessary to design the patterns and cut the fabrics in such ways that the pleats may be of the proper proportions and in the desired positions. It will be apparent that the above-described operations require considerable designing and cutting skill and introduce some rather serious problems, particularly in the production of ready-to-wear garments. For example, in pleated trousers, the pleats must be accurate in position, size, in their relation to each other and to the waistband of the garment. So long as it is possible to provide such trousers in the proper sizes, no difficulty is encountered. However, when the size of the waistband must be increased or decreased, some of the pleats must be removed or altered to conform to the change in the waistband, thereby necessitating an almost complete remaking of the upper portion of the garment.

Likewise when taking up or letting out the waistband of trousers having pleats therein, the relative positions of the pleats may be altered thus changing the entire fit and hang of the garment and producing an undesirable effect.

In accordance with the present invention, I have produced pleated garments of simple construction which may be readily adjusted to a desired waistband size without altering the fit or hang of the garments or without redesigning the garments.

In general, the garments embodying the present invention are of conventional construction with the exception that additional material from which pleats are to be formed is provided in the front panels and the waistband portion of the garments. Also, differing from the usual construction, the excess material is not stitched into permanent pleats but instead is pleated by an adjustable belt construction which permits considerable variation in the width of the pleats while simultaneously adjusting the waistband of the garment to the desired size.

For a better understanding of the present invention, reference may be had to the accompanying drawing, in which

Figure 1 is a front view of a typical form of 55

garment embodying the present invention; and Figure 2 is a plan view of a portion of the waistband of the garment disclosing details of construction of the same.

As shown in Figure 1, the invention is applied to a pair of trousers 10, although it will be understood that the garment may be shorts, skirts, bathing trunks or any other type of nether garment. As shown, the trousers have the usual leg portions 10a, fly 11 and a waistband portion generally indicated as 12. At opposite sides of the fly 11 are fixed short belt straps 13 and 14, the former having a buckle 15, or any other desired type of adjustable connecting device thereon, for cooperation with the strap 14. The inner ends of the straps 13 and 14 may be secured in any desired way to the garment, such as, for example, by means of stitching 16, so that they are a fixed part of the garment.

Outwardly of the inner ends of the belt straps 13 and 14 are a pair of loops 17 and 18 which are secured to the waistband portion 12 of the garment. As shown particularly in Figure 2, the loops 17 and 18 may be secured to the waistband portion 12 by means of a strip of fabric 19 matching the fabric of the garment 10, having its inner end 19a stitched to the waistband portion 12 of the garment, passed through the loop 17, connected around the sides and back of the garment, through the loop 18 and then having its other end 19b turned back and stitched to the waistband portion 12 of the garment, thereby securing the loops 17 and 18 in position. If desired, the strip 19 need not be extended around the sides and back of the garment. It should be noted that the creases 20 in the garment are adjacent to the forwardmost edges of the waistband straps 19.

The material between the attached ends of the straps and the loops in the waistband portion and in the front panels of the trousers is in excess of normal requirements and is included to form potential pleats of variable size in the front panels of the garments.

Inward movement of the loops 17 and 18 with consequent formation of pleats in the front panel of the garment and decrease in size of the waistband of the garment may be produced by passing the strap 13 through the loop 17, the strap 14 through the loop 18, and drawing the straps together and buckling them in front of the garment as shown in Figure 2. As the straps are drawn up more and more to decrease the size of the waistband, the fabric between the fixed ends of the straps 13 and 14 and the loops 17

and 18, respectively, in the front of the garment is folded over more and more as shown in Figure 2 to vary the width of the pleats 21 and 22. At the same time, the center portion of the garment between the fixed ends of the belt straps 13 and 14 is drawn out and thus wrinkling of the front of the garment is entirely avoided and alteration of the hang of the garment likewise is minimized. Similarly, since the waistband portion 12 extending around the back of the garment between the loops 17 and 18 is unchanged in size, there is no bunching of the material at the sides or in the back, and likewise no alteration in the fit of this portion of the garment.

The position of the loops 17 and 18 control the location of the pleats. With the loops properly positioned, the pleats will always bear a predetermined relationship to the sides and back of the garment. Thus for example, the pockets 20 will not be shifted in the garment and the pleats are always a fixed distance from the pockets regardless of the adjustment of the straps 13 and 14.

From the preceding description it will be clear that pleated garments may be produced in accordance with the present invention in such a way that size adjustments may be made without alteration of the garment or without displacing the pleats. Moreover, the amount of work required to produce such garments is greatly decreased and a single pattern may serve for the production of garments which fit individuals of varying size. The present invention therefore lends itself particularly to the manufacture of 35 ready-to-wear or mass-production garments.

It will be understood, of course, that the belt straps 13 and 14 may be of any desired type. For example, they may be made of the same type of material as the garment, in matching or contrasting colors. They may be leather or other material, with buckles or clasps of any desired type, and the loops 17 and 18 of the garment may be of any desired type of material such as metal, plastic, bone and the like, and of any 45 desired color or design.

It will be apparent from the above disclosure that constructions embodying the present invention may be applied with equal facility to pleated formal or sportswear of all types, to working garments for either men or women, and, therefore, there is a wide utility for the construction of the present invention. Accordingly, it will be understood that inasmuch as the invention is susceptible to wide modification in its details of construction without departing from the invention, the above described example should be considered as illustrative only and not as limiting the scope of the following claims.

I claim:

1. A garment having a leg covering portion, a waistband portion, and means for forming pleats in the front portions of said garment and adjusting the size of said waistband portion by varying the width of said pleats comprising a pair of flexible members having their inner ends fixed in spaced relation to the front of the outside of said waistband portion, loops for receiving said flexible members attached to the front

of the outside of said waistband portion in spaced relation to the fixed ends of said straps, and means on said flexible members for detachably and adjustably connecting said flexible members to draw said loops inwardly toward the center of the front of the waistband of said garment and form pleats in the material in the front of said garment between said fixed ends of said flexible members and said loops.

2. A garment having a leg covering portion, a waistband portion and means for forming pleats in the front of said garment for adjusting the size of said waistband portion by varying the width of said pleats comprising a first strap having one end secured at one side of the center of the front of the outside of said waistband portion, a second strap having one end secured at the other side of the center of the front of the outside of said waistband portion in spaced relation to said first strap, loops secured to the front of the outside of said waistband portion in spaced relation to and outwardly of each of secured ends of said straps for slidably receiving said straps, and means on said straps for adjustably connecting them in the front of said waistband to cause the material in the front and the waistband portion of said garment between said straps and the corresponding loops to be formed into pleats upon tightening said straps.

3. A garment having a leg covering portion, a waistband portion and means for forming pleats of variable size in the front of said garment and adjusting the size of said waistband portion by varying the width of said pleats comprising a pair of loops attached in spaced apart relation to the outside of the front of said garment at said waistband portion, a pair of belt straps having their inner ends spaced apart and attached to the outside of said waistband portion between said loops and free outer ends adapted to be passed through said loops, and means on said straps for adjustably connecting their free ends to permit said straps to be drawn up, thereby pulling said loops toward each other and forming pleats in the material in the front and in the waistband portion of said garment between said loops and the inner ends of said straps.

4. A garment having a leg covering portion, a waistband portion, a waistband strap extending around the outside of the sides and back of said waistband portion and terminating in spaced apart ends in the front of said waistband portion, a loop secured to each end of said waistband strap, a pair of flexible members each having an end secured to the outside of said waistband portion between said loops, said ends being spaced apart from each other and from said loops and defining areas of excess material adapted to be formed into pleats in the front of said garments between said loops and the corresponding secured ends of said straps, and adjustable connecting means on said members permitting said members to be connected after they have been passed through said loops, and adjusted to form said excess material into pleats of variable size in accordance with the adjustment of said members.

ERNEST A. DE ROSE.
